Specification for Design.

Patented Jan. 17, 1922.

Application filed March 23, 1921. Serial No. 454,909. Term of patent 3½ years.

To all whom it may concern:

Be it known that we, CROFTON C. HOLDEN and EDMUND P. HADLEY, (said HOLDEN is a citizen of the United States, said HADLEY a subject of the King of Great Britain,) both residing at Leominster, in the county of Worcester and State of Massachusetts, have invented a new, original, and ornamental Design for a Bag Frame, of which the following is a specification, reference being had to the accompanying drawing, in which—

Fig. 1 is a side elevation of a bag frame showing our new design; and

Fig. 2 is an end elevation thereof.

We claim:

The ornamental design for a bag frame as shown.

In testimony whereof we have hereunto affixed our signatures.

CROFTON C. HOLDEN.
EDMUND P. HADLEY.
